LOCOMOTIVE STOKER

Charles J. Surdy, Erie, Pa., assignor to The Standard Stoker Company, Incorporated, a corporation of Delaware

Application May 20, 1939, Serial No. 274,742

5 Claims. (Cl. 110—105.5)

This invention relates to locomotive stokers of the type which feed through an opening in the firebox backwall.

5 A locomotive stoker of the general type specified includes a conduit for delivering coal to a distributing mechanism positioned at the firing opening in the firebox backwall; the distributing mechanism consisting of a pressure fluid jet arranged to project fuel across the upper surface 10 of a distributing table which extends through the firing opening and into the firebox. The distributing table is provided with suitable ribs for causing equal distribution of coal over the firebox. With the distributing table so positioned 15 in a firing opening of the size and design hereinbefore specified it forms, together with the upper marginal edge of the firing opening, a restricted tunnel formation through which mechanics must enter the firebox.

20 One object of this invention is to connect the distributing table to an exterior movable portion of the stoker conduit whereby movement of the latter will cause withdrawal of the distributing plate from its operative position in the firing opening. In this manner, the restricted tunnel formation may be readily eliminated when desired, thereby rendering access to the interior of the firebox more convenient.

25 A still further object of this invention is to provide a stoker which feeds through a firing opening in a wall of the furnace, the stoker being provided opposite the firing opening with an exterior wall pivotally mounted to swing away from the furnace wall and also carrying a distributing table mounted thereon for swinging movement, together with said pivotally mounted exterior wall, in a direction away from the firing opening.

30 It is also an object of this invention to provide a stoker which feeds through a firing opening in the wall of the furnace and having its upper portion which embraces such opening provided with an aperture adapted to be covered by a suitable door; the stoker being provided 35 immediately beneath such door with an exterior wall pivotally mounted to swing away from the furnace wall and carrying a distributing table secured thereto for swinging movement away from its position in the firing opening.

35 A more specific object of this invention is to utilize the door, as above specified, for the purpose of maintaining the pivotally mounted exterior wall of the stoker in operative position.

40 Other objects reside in the particular formation of the parts, and their relation one with

another as will become apparent from the following description when read in connection with the accompanying drawings, in which

Figure 1 is a fragmentary longitudinal section taken through the rearward portion of a locomotive firebox showing the stoker according to this invention partly in similar section and partly in side elevation;

Figure 2 is a sectional view through the firing opening taken along the line 2—2 of Figure 1;

Figure 3 is an end elevation of the structure illustrated in Figure 1 taken on line 3—3 thereof with portions removed and parts shown in section;

Figure 4 is a sectional view in plan taken along the line 4—4 of Figure 1; and

Figure 5 is also a sectional view in plan taken along the line 5—5 of Figure 1.

Referring now to these drawings, L indicates a locomotive having a boiler 10 provided with a backwall 11 in which there is an opening 12 providing an entranceway into the firebox or furnace 13. In most cases the firing opening 12 is in the form of an ellipse, the major and minor axes of which measure approximately 20 inches and 16 inches, respectively. A stoker, generally indicated by S, feeds into the firebox 13 through the firing opening 12 and includes a conduit element 14 secured by bolts 15 to a terminal member 16 which in turn is secured by bolts such as 17 to the backwall 11. The terminal member 16 includes side walls 18, 19 and a top wall 20; the side and top walls embracing the firing opening 12. At their forward ends the side and top walls extend closely adjacent the marginal edge of the firing opening 12 and in rearward extent flare laterally to provide, opposite said firing opening 12, an aperture 21 which is closed in part by the pneumatically operated firedoor 22 and the rear exterior wall 23 of the terminal member 16.

On its upper rearward wall the conduit element 14 is provided with a pair of spaced ears or lugs 24, 25 which fit between complementary lugs 26, 27 formed with the exterior wall 23. A pin 28 is passed through the lugs of the conduit element 14 and the terminal portion 16 to form a pivotal connection about which the exterior wall 23 may swing. On each lateral side thereof the rearwall 23 has inwardly turned flanges 29 and 30 the bottom of each of which is adapted to rest upon a corresponding ledge 31, 32 of the terminal member 16. The firing door 22, when closed, retains the exterior wall 23 in the position shown in Figure 1.

Closely adjacent the lower marginal edge of firing opening 12 and disposed along the plane of the outer surface of the backhead 11 is a pressure fluid nozzle 35 having provided therein 5 a plurality of chambers 36 which receive fluid under pressure from suitable connections such as 31. The nozzle 35 is provided with forwardly directed jet apertures 38 for issuing blasts of pressure fluid across the upper surface 39 of a 10 distributing table 40. Ribs 41, 42 are formed on the upper surface 39 of the table 40 and co-operate with the blasts of pressure fluid issuing from the nozzle 35 for distributing fuel to all 15 portions of the firebox as it is delivered by the stoker S. On each lateral side thereof the distributing plate 40 is provided with an upstanding wall 43, 44, the upper portion of each of 20 said walls being in abutting relation with the forward ends of respective flanges 29, 30 of the pivotally mounted exterior wall 23. Aligned bolts 45, 46 passing respectively through the walls 43, 44 of the distributing table 40 and through the inwardly turned flanges 29, 30 of the pivotally 25 mounted exterior wall 23 are utilized to form a pivotal connection between the wall 23 and the distributing table 40. The rearward edge of the upper surface 39 of the distributor table 40 is engaged beneath the forward end of the jet nozzle 35, the relation of parts being such that by 30 pushing the distributing table forwardly, the latter can be disengaged from the nozzle 35 as shown by the dot and dash lines in Figure 1.

During normal operation of the device fuel is 35 conveyed through the conduit element 14 and terminal member 16 in a manner well-known in the art and is deposited on the upper surface 39 of the plate 40 from which it is swept forwardly into the firebox by the action of the pressure fluid blasts issuing from the jet nozzle 35. Whenever 40 it is necessary to inspect the condition of the fire, the firedoor 22 is opened in the customary manner and inspection of the fire is made through that portion of the aperture 21 which is above the pivotally mounted wall 23. Since the upper 45 end of the top wall 23 extends a considerable distance above the lower marginal edge of the firing opening 12, that portion of the firing opening 12 above the plane of such wall 23 usually is insufficient to allow mechanics to enter the firebox. 50 With the present invention, whenever it is desired to enter the firebox, the firedoor 22 is opened and then the distributing table 23 is tilted so as to disengage the jet nozzle 35. When the parts are in this position the pivotally mounted 55 rear wall 23 may be swung about the axis of the supporting pin 28. It will, of course, be understood that when the wall 23 is swung rearwardly, the distributing table 40 is withdrawn from its operative position in the firing opening 60 as indicated by the dotted lines in Figure 1. In order that the lower wall 50 of the distributing table 40 may not be engaged by the jet nozzle 35 during withdrawal of the distributing table a rib 51 is provided which, during withdrawal of the 65 plate 40, rides along the upper forward edge of the nozzle 35 to prevent downward movement of the table 40.

With the pivotally mounted exterior wall 23 and distributing table 40 removed from operative position, the only restriction then offered to entrance into the firebox is formed by the upper edge of the firing opening 12 and the upper end of the jet nozzle 35. However, since the latter is very narrow this arrangement does not, in practice, constitute an obstruction because

there is no extensive tunnel formation through which mechanics must enter or a ledge over which the mechanic must crawl. It will also be apparent that the pivotal arrangement of the distributor plate 40 and the exterior wall 23 provides a very convenient way of withdrawing the distributing table 40 from its operative position whenever it is desired to replace it. By this arrangement of parts it is possible to replace the table from a position exteriorly of the furnace 13. 10

To those familiar in the art it will be apparent that a stoker according to the present invention can be readily applied to locomotives having firing openings of existing form. Also, the arrangement provides free access to the interior of the 15 firebox.

While the invention as illustrated is shown applied to the locomotive, it will be obvious that certain features are capable of more wide-spread use. The following claims define the invention. 20

I claim:

1. In a furnace having an upright wall provided with a firing opening therethrough, a stoker for feeding fuel into said firebox comprising a conduit element having a terminal portion communicating with said firing opening, said terminal portion having a rear wall pivotally mounted for movement away from said firing opening about a horizontal axis, a distributing table positioned in said firing opening, and means for pivotally connecting said distributing table to said pivotally mounted rear wall for movement about a horizontally disposed axis. 25

2. In a furnace having an upright wall provided with a firing opening therethrough, a stoker for feeding fuel into said firebox comprising a conduit element having a terminal portion communicating with said firing opening, said terminal portion having a rear wall pivotally mounted for movement away from said firing opening 30 about a horizontal axis, a distributing table positioned in said firing opening, means for pivotally connecting said distributing table to said pivotally mounted rear wall for movement about a horizontally disposed axis, and means for restraining downward movement of said pivotally mounted distributing table from its operative position. 35

3. In a furnace having an upright wall provided with a firing opening therethrough, a stoker for feeding fuel into said firebox comprising a conduit element having a terminal portion communicating with said firing opening, said terminal portion having a rear wall pivotally mounted for movement away from said firing 40 opening about a horizontal axis, a pair of flanges, one at each side of said pivotally mounted rear wall, extending toward said firing opening, a distributing table positioned in said firing opening, a pair of upstanding walls, one on each side of 45 said distributing table and means passing through the said upstanding walls of said distributing table and through the inwardly extending flanges of said pivotally mounted rear wall forming a pivotal connection for said distributing table 50 whereby the latter may swing with respect to said pivotally mounted rear wall on a horizontal axis. 55

4. In a furnace having an upright wall provided with a firing opening therethrough, a stoker for feeding fuel into said firebox comprising a conduit element having a terminal portion communicating with said firing opening, said terminal portion including a top wall and side walls embracing corresponding portions of the firing opening and being provided opposite said firing 60

opening with an aperture defined by the rear edges of the top and side walls, a door closing a portion of such aperture, said terminal portion immediately beneath said door having a rear wall 5 closing the remainder of said aperture and being pivotally mounted for movement away from said firing opening about a horizontal axis, a distributing table positioned in said firing opening, and means for pivotally connecting said distributing table to said pivotally mounted rear wall for movement about a horizontally disposed axis.

5. In a furnace having an upright wall provided with a firing opening therethrough, a stoker for feeding fuel into said firebox comprising a conduit element having a terminal portion communicating with said firing opening, said terminal portion including a top wall and side walls 15 embracing corresponding portions of the firing

opening and being provided opposite said firing opening with an aperture defined by the rear edges of the top and side walls, a door closing a portion of such aperture, said terminal portion immediately beneath said door having a rear wall 5 closing the remainder of said aperture, said rear wall being pivotally mounted for movement away from said firing opening about a horizontal axis, a stop element limiting pivotal movement of said rear wall in a direction toward said firing opening, said door normally restraining rearward movement of said rear wall about its pivotal mounting, a distributing table positioned in said firing opening, and means for pivotally connecting said distributing table to said pivotally mounted rear wall for movement about a horizontally disposed axis. 10 15
